(57) **CLAIM**

The ornamental design for an electronic payment card with biometric verification means positioned thereon, as shown and described.

DESCRIPTION

FIG. 1 is a front perspective view of the electronic payment card with biometric verification means positioned thereon.

FIG. 2 is a rear perspective view of the electronic payment card with biometric verification means positioned thereon.

FIG. 3 is a front plan view of the electronic payment card with biometric verification means positioned thereon.

FIG. 4 is a rear plan view of the electronic payment card with biometric verification means positioned thereon.

FIG. 5 is a right side view of the electronic payment card with biometric verification means positioned thereon.

FIG. 6 is a left side view of the electronic payment card with biometric verification means positioned thereon; and,

FIG. 7 is a top view of the electronic payment card with biometric verification means positioned thereon.
